CAN BRACING MEANS

Robert G. Hussong, Los Angeles, Calif., assignor
to Petersen Show Case & Fixture Company, a
corporation of Nevada

Application July 31, 1945, Serial No. 607,932

1-Claim. (Cl. 220—15)

1 This invention relates to bracing means for bracing or holding an article in a fixed position; while the invention may be used in various situations, it is intended, and is described, in the following specification as performing the function of bracing from which ice cream and sherbets are dispensed by means of a scoop held in the attendant's hand. The cans referred to are deep cylindrical cans sitting loosely in a box-like casing or metal box. When the ice cream in the can is hard, as it should be, considerable force must be exerted through the scoop. The attendant must hold the can with one hand while operating the scoop with the other. The bracing means about to be described is intended to be employed for holding such ice cream cans in a substantially fixed position when the attendant is scooping ice cream or sherbet from the same.

One of the objects of this invention is to provide very simple and inexpensive bracing means for holding such a can in a fixed position when scooping out the ice cream.

One of the objects of the invention is to provide apparatus of this kind which is so constructed that it avoids the use of coil springs, which incidentally avoids the necessity for constructing seats or guides for such springs.

Another object of the invention is to provide bracing means of this character in which a resilient member in the form of a bar is employed, having inherent capacity for adjustment so that if the force exerted by the bar upon the article or container becomes weakened with use, it can be readily adjusted without the use of special tools to increase the force with which it will press against the article or container for holding it in place.

In its construction the invention, as described in the following specification, includes the use of a resilient bar that engages the side of the article or container that is to be braced and held in a substantially fixed position, and the ends of this bar cooperate with fixed means to engage the same and cause the bar to exert spring pressure against the side of the container that it is holding. And one of the objects of the invention is to construct a relatively fixed holding means or engaging means for the ends of the bar in such a way as to facilitate placing the bar in position, that is, in its working position in which it will exert its pressure against the side of the container.

Further objects of the invention will appear hereinafter.

2 The invention consists in the novel parts and combinations of parts to be described hereinafter, all of which contribute to produce an efficient bracing means.

A preferred embodiment of the invention is described in the following specification, while the broad scope of the invention is pointed out in the appended claim.

In the drawing:

Figure 1 is a horizontal section through a corner of an outer container or casing in which articles such as ice cream containers or cans are held. This view illustrates a corner of such an outer container with two inner containers or cans within the same, and illustrates my bracing means set for holding the cans in their fixed positions. In this view the other portions of the outer container are broken away.

Figure 2 is a vertical section through the outer container on the line 2—2 of Figure 1, and further illustrating the details of construction.

Figure 3 is a vertical section taken about on the line 3—3 of Figure 1 and particularly illustrating the relatively fixed means employed at an intermediate point within the outer container for cooperating with the adjacent end of one of the saddle bars that hold the containers in position.

Referring more particularly to the parts, and particularly to Figure 1, the dotted lines 1 and 2 indicate the outlines of two ice cream cans which are illustrated as disposed within an outer casing or outer container 3. This outer container usually employed with such cans is of rectangular or square form so that it presents two walls 4 and 5 at each corner, that are disposed at right angles to each other. The wall 4 may be considered as constituting a side wall of the outer container or casing, while the wall 5 may be considered an end wall.

In the present disclosure of this invention it is assumed that the casing 3 is wide enough to receive more than one row of inner containers or cans 1 and 2, and in applying my invention in such a situation I provide a saddle bar 6 corresponding to each of the cans, and this saddle bar, as illustrated, has a curved body 7 that is adapted to fit approximately to the curvature of the periphery of the can to which it is applied. In the present instance this body 7 has integral end portions or shanks 8, and these shanks perform the function of engaging with means cooperating to hold the saddle bar pressed against the side of the can. In the present instance the engaging means for the shanks 8

preferably consists of spurs extending in the general direction in which the axis of the container extends. In the present instance, these spurs project upwardly, that is to say, they comprise upwardly extending dog plates 9 and 10 having substantially the form illustrated in Figure 3. The dog plate 9 located at the left of the figure is secured at its lower end by welding or rivets to a Z bar 11 that is secured to the inner face of the side wall 4 of the outer container. The other dog plate 10 is attached to the adjacent flange of a channel bar 12 that extends transversely within the outer container 3 and preferably is substantially parallel with its wall 4.

The ends of the shanks 8 are preferably provided with laterally extending tongues or hooks 13 which assist in preventing the saddle bars from becoming dislodged for any reason, as for example, where the outer containers are transported loaded with cans.

In practice I prefer to have one of the dog plates or clips 9 and 10 extend to a higher level than the other, for example, as illustrated in Figure 2 the clip or dog plate 10 extends to a higher level than the dog plate 9, which is disposed over toward the left side of the outer container. This increased length or height of the dog plate on one side facilitates placing the saddle bars in position because the shank 8 on the side adjacent to the tallest or highest dog plate 10 can be engaged with that dog plate first; after which the shank 8 at the opposite side would be pressed toward the forward wall 5 of the outer container to a point above and adjacent to the dog plate 9, whereupon the bar would then be shoved down bodily toward the bottom 14 of the outer container until the ends of the shanks 8 are seated respectively on the web of the Z bar 11 and on the upper face or web of the channel 12.

It is obvious also that if the can body has sufficient stiffness and resiliency it may supply sufficient spring effect to make it unnecessary to have any substantial amount of resiliency in the saddle bars or in the dog plates.

If the saddle bars tend to lose their holding effect after considerable use, their holding power can be restored by applying a bending force against the middle of their curved bodies on their convex side. This will "straighten" the bar

5 somewhat which will renew its "follow up" holding effect.

It will be noted that the walls such as the wall 5 against which the cans are pressed, operate as relatively fixed means for opposing and resisting the pressure exerted by the bars. While it is convenient to use the wall 5 for this purpose, it is obvious that such fixed means might consist of a stop or short post projecting up from the bottom of the outer container to engage the side of the clamped can.

Many other embodiments of this invention may be resorted to without departing from the spirit of the invention.

15 I claim as my invention:

Bracing means for holding an article such as a container in a substantially fixed position within an outer casing having side walls including a first wall, and a second wall disposed substantially at right angles to the first wall, said bracing means including a saddle bar to engage a portion of the periphery of the article on a side thereof substantially opposite to said first wall, engaging means on the interior of the second wall for engaging the end of said bar on the side thereof remote from the first wall, exerting pressure reacting against the resilience of the bar, a transverse fixed bar within said outer container disposed in a plane transverse to said first named bar, and substantially parallel with the second wall, and engaging means on the fixed bar for engaging the other end of said saddle bar, both of said engaging means being located so that when the saddle bar is engaging the inner container the pressure of the engaging means causes the bar to press itself against the side of the container to force the same against the said first wall.

40 ROBERT G. HUSSONG.
